ABSTRACT

A peripheral wall with two spaced partitions extending inwardly therefrom, a cone-shaped floor with a central aperture and peripheral holes, and a lid with an arcuate opening and a downwardly extending skirt comprise a granule dispensing regulator positionable in a container neck. The partitions and wall therebetween define a well which is primed by upending and uprighting the container. Granules are dispensed when the container is next upended.

GRANULE DISPENSING REGULATOR

This invention pertains to dispensers generally, and more specifically to granule dispensers. In particular it relates to a dispensing regulator which regulates the dispensation of granules from a container.

Granule dispensers which dispense regulated or measured amounts of granules are well known in the art. Examples of conventional granule dispensers are taught by M. J. Klygis and W. F. Lodding in their U.S. Pat. No. 3,342,383 and by C. M. Day in his U.S. Pat. No. 1,957,326. Typically, the dispenser has a well in the neck of the container which accommodates the desired amount of granules that are to be dispensed. This well is filled by turning the container upside down and then right side up. The well is thus primed with granules which are then dispensed through an opening in the top of the container above the well when the container is next upended.

These dispensers dispense a measured amount of granules each time the container is tipped. However, if the measured amount is not quite enough to satisfy the user, he must either settle for less than what he wants or pour out another measure and settle for more than he wants. It is not always possible to choose an amount that would be satisfactory to all users. It would be preferable to be able to increase slightly the amount of granules dispensed while the container is upside down.

Accordingly, it is an object of this invention to provide a granule dispensing regulator which can dispense a predetermined amount of granules each time, if desired, and which can also increase said predetermined amount, as desired, without retipping the container.

It is another object of the present invention to provide a granule dispensing regulator with a variable size well.

A further object of this invention is to provide a granule dispensing regulator with multiple wells of various sizes.

These and other objects and advantages of the present invention are achieved by a granule dispensing regulator, positionable in the neck of a container, for regulating the dispensation of granules therefrom. This regulator comprises a peripheral wall with seating means, such as a peripheral lip connected to the top of, and extending outwardly from the wall, for seating the wall in the neck of a container. Peripherally connected to the wall is an essentially cone-shaped floor with its apex extending toward the plane of the top of the wall. A pair of spaced partitions extend inwardly from the wall and upwardly from the floor to the plane of the top of the wall, the partitions and the wall therebetween defining three sides of a well. A lid is seated on top of the wall and has a portal opening between its center and its periphery. The portal opening is located above the well and is no wider than the well. A skirt extends downward from the edge of the portal opening nearest the lid center toward the floor. The skirt is located between the partitions at an intermediary point of their inward extension. The lid, the skirt, and the portions of the partitions extending beyond the intermediary point define four sides of an interim region. Flow means, such as an aperture in the apex of the floor, allow granules to pour forth from the container into the interim region when the container is tipped upside down. Return means, such as a plurality of return openings, peripher-

ally disposed in the floor externally of said well, allow granules to return to the container when the container is returned upright.

The invention is described in greater detail in conjunction with the accompanying drawings in which:

FIG. 1 is a perspective assembly view of a granule dispensing regulator according to one embodiment of this invention;

FIG. 2 is a plan view of the regulator of FIG. 1;

FIG. 3 is an elevational cross-sectional view of the regulator of FIG. 2 taken along section 3-3;

FIG. 4 is a perspective view of a container with the regulator of this invention seated therein;

FIGS. 5 and 6 are cross-sectional views of the regulator of FIG. 1 disposed within a container and in the process of being used;

FIG. 7 is a perspective assembly view of a granule dispensing regulator according to another embodiment of this invention;

FIG. 8 is a plan view of the regulator of FIG. 7;

FIG. 9 is an elevational cross-sectional view of a multiple-well granule dispensing regulator according to yet another embodiment of this invention; and

FIG. 10 is a plan view of a multiple-well granule dispensing regulator according to still another embodiment of the present invention.

Referring now to FIGS. 1, 2 and 3, there is shown a granule dispensing regulator 1 comprising a cylindrical wall 2 with an external annular lip 4 at the top. An essentially conically shaped floor 6 is peripherally connected to the bottom of the wall 2 and extends upwardly within the wall 2 toward the plane of the lip 4. The apex of the conical floor 6 is truncated by an aperture 8. Spaced about the periphery of the floor 6 are return openings 10. The significance of the aperture 8 and the plurality of return openings 10 will become clear subsequently. Two spaced partitions 12a and 12b extend vertically from the floor 6 to the plane of the lip 4 and inwardly from the wall 2.

A well 14 for temporarily receiving a desired amount of granules comprises a semi-enclosure bounded partially by the partitions 12 and the wall 2 therebetween. A portion 6a of the floor 6 between the partitions 12 forms the bottom of the well 14 and may follow the contour of the rest of the conically shaped floor 6, or it may be specially shaped, as shown, for example, to accommodate a greater amount of granules. The aforementioned return openings 10 are external to the well 14. The floor portion 6a as shown extends from the wall 2 to a vertical extension 6b of the floor 6, said extension 6b forming another boundary of the well 14.

A lid 16 is seated, preferably permanently, on the lip 4 and has an arcuate portal opening 18 above the well 14. The opening 18 is preferably arcuate to conform to the shape of the well 14, however, it may have any other shape so long as it is otherwise consistent with the teachings of this invention. For reasons which will become clear subsequently, the width of the opening 18 is no greater than the width of the well 14.

A skirt 20 extends vertically downwardly from the innermost edge 22 of the opening 18 and between the partitions 12, as shown, to essentially the plane of the aperture 8. The skirt 20 could alternatively be connected to the partitions 12 rather than to the lid 16, so long as it is essentially in the same position. Specifically, the skirt 20 is aligned vertically with the edge 22

and the floor extension **6b** and is in continuous contact with the edge **22**.

FIGS. 4, 5 and 6 show the regulator **1** of this invention seated in a neck **24** of a granule container **26**. The regulator **1** can be secured in the neck **24** by conventional means. For example, it can be positioned with the lip **4** seated on the rim **28** of the container **26** and held there by a cap **30** which is screwed onto the container **26**, as shown. The cap **30** has an arcuate port **32** which is aligned with and is of the same size and shape as the arcuate portal opening **18** in the lid **16**. If desired, the port **32** can have a perforated cover therein to facilitate sprinkling the granules rather than pouring them. This might be desirable if the granules are salt or spices as opposed to sugar or instant coffee which are usually poured.

As an alternative to securing the regulator **1** in the container by a cap, the wall **2** could be threaded on the outside and the neck **24** could be threaded internally to receive the threaded wall. The wall could then be screwed into the neck until the lip **4** rested on the rim **28**. A cap would then be needed merely to cover the container, rather than to hold the regulator **1** in place, in which event there would be no need for an arcuate port in the cap.

The operation of the regulator **1** is best described in conjunction with FIGS. 5 and 6. Initially, the container **26** is tipped from an upright position to the inverted position shown in FIG. 5. Granules **34** pour through the aperture **8** in the floor **6** and accumulate in an interim region **36** partially bounded by the lid **16**, the skirt **20** and the partitions **12**. The container **26** is then returned to an upright position, as in FIG. 6. During this step, the granules in the interim region **36** pass between the skirt **20** and the floor **6** into the well **14**. The well **14** is now said to be primed.

When the container **26** is next tipped into the position of FIG. 5, the granules in the well **14** pour through the opening **18** and through the port **32**. Simultaneously granules from within the container **26** once again fill the interim region **36**. Thereafter, during each cycle of tipping and returning the container **26**, a measured amount of granules are dispensed from the well **14** through the port **32**, and the well **14** is reprimed with another measured amount of granules.

In the course of tipping the container **26**, granules **34** accumulate to either side of the interim region **36**. When the container **26** is then tipped back to the upright position, these granules fall back into the container **26** via the return openings **10**.

The conical shape of the floor **6** is preferred in order to encourage the flow of granules **34** through the opening **8** when the container is upside down and back through the return openings **10** when the container is returned upright. The size of the opening **8** should be large enough to allow the granules in the container to pour freely through the opening **8**. The shape of the floor portion **6a** may be flat, as shown, or rounded, if desired, and may be deeper than as shown, if necessary to accommodate the desired amount of granules.

In order to accomplish the regulation of the granules as they are dispensed in the aforementioned manner, the location of the skirt **20** relative to the floor **6** is important. The skirt **20** must extend vertically downward essentially to the plane of the aperture **8** and arcuately from partition **12a** to partition **12b** and should be located essentially above the extension **6b**. The shortest

distance between the skirt **20** and the floor **6** is herein identified as distance **38** and is limited to within the range essentially from 1 to 2 times the largest linear dimension of the granules being dispensed and is preferably 1½ times that dimension. This provides the necessary amount of restriction on the flow of granules from the interim region **36** to the well **14**. If the distance **38** is larger, the granules will tend to pour freely into the well **14** and out the port **32** when the container is tipped, instead of accumulating in the interim region **36**, thereby eliminating the regulation. If the distance **38** is smaller, the granules would jam there and stop flowing into the well **14** altogether, thereby eliminating the dispensation.

15 A particular advantage of this invention is that the user may increase the amount of granules emerging from the port **32** by a fraction of the measured amount accommodated by the well **14**. If the amount desired by the user is more than the measured amount but less than twice the measured amount, the user can jiggle the container slightly while it is upside down until the desired amount of granules is dispensed. This can be accomplished because of the juxtaposition of the skirt **20** and the floor **6** and the size of the distance **38**. While 20 the granules **34** do jam between the skirt **20** and the floor **6** when the interim region **36** is filled, the slight 25 jiggling of the container will loosen a small amount of those granules, allowing them to enter the well **14** and emerge from the port **32**.

30 If the skirt **20** does not extend down to the plane of the aperture **8**, the granules will tend to pour into the well **14** and through the port **32** when the container is tipped rather than accumulate in the interim region **36**. If the skirt **20** extends beyond the plane of the aperture 35 8, it will impede the flow of granules into the well **14** when the container is jiggle in the inverted position of FIG. 5.

In the Klygis patent, the plane of the free edge **20** is 40 analogous to the plane of the aperture **8** herein, and the wall **33** therein is analogous to the skirt **20** herein. It will be seen that in Klygis the wall **33** extends beyond the plane of the free edge **20**. Klygis points this out on page 3 and further indicates that this "... prevents material flowing outwardly of the container body from admixing with the portion P1 being dispensed ..." (page 3, lines 32 to 35). In the Day patent, the plane of the edge of the baffle **14** is analogous to the plane of the aperture herein, and the wall **12** therein is analogous to the skirt **20** herein. It is seen that in Day, the wall **12** 45 extends below the plane of the edge of the baffle **14**. Day points out on page 2, lines 97 to 104, that because of the relative locations of the edge of baffle **14** and the end of wall **12**, further flow of granules or particles into the measuring compartment **10** is precluded. In both Klygis and Day, it is clearly pointed out that while the container is inverted, once the measuring chamber or dispensing chamber is charged with the desired or measured amount of material, further flow or admixing is precluded. No suggestion is made to jiggle the upturned 50 container to slightly increase the dispensed amount. Indeed the very opposite is suggested; nor are they able to do so with those inventions.

In FIGS. 7 and 8, there is shown another embodiment 55 of the present invention having a variable size well **14**. The lid **16** is rotatably seated on the lip **4** in this embodiment, and partition **12b** is attached to the lid **16** instead of to the wall **2** and floor **6** as in FIGS. 1, 2 and

3. Two sets of notches 40a and 40b set in the top of the lip 4 at opposite ends thereof are designed to receive the bottom ends 42a and 42b of stubs 44a and 44b, respectively, which protrude beneath opposite ends of the lid 16. The lid 16 can be revolved relative to the lip 4 by pushing in opposite directions on the top ends 46a and 46b of the stubs 44a and 44b, respectively. When the lid 16 is turned clockwise, partition 12b approaches partition 12a, thereby diminishing the size of the well 14. Turning the lid 16 counterclockwise increases the size of the well 14. Thus, the lid 16 can be calibrated so that each position of the lid 16 corresponds to a predetermined size of the well 14, e.g. $\frac{1}{2}$ teaspoon, 1 teaspoon and 1 tablespoon.

Partition 12a has a wing 13 laterally attached thereto externally of the well 14 and in the plane of the lip 4. The arcuate width of the wing 13 is determined as follows: When the lid 16 is rotated clockwise to the last calibrated position, corresponding to the smallest separation between partitions 12a and 12b, the arcuate width of the wing 13 is equal to at least the difference between the arcuate width of the opening 18 and the arcuate separation between the partitions 12a and 12b. The purpose of the wing 13 is to prevent granules from flowing freely along the outside of the well 14 alongside partition 12a and thence through the portion of the opening 18 extending laterally beyond the well 14 when the lid 16 has been rotated counterclockwise and the container is upside down.

FIG. 9 shows another embodiment of this invention wherein the device comprises three wells 14a, 14b and 14c of various sizes. As shown, the wells 14 vary in depth and have the same size arcuate width. It is preferable that the wall 2 extend, as shown, to the bottom of the deepest well 14a for ease of manufacturing. However, the wells 14 may extend below the bottom of the wall 2, if desired.

The lid 16 in FIG. 9 is similar to the one in FIGS. 7 and 8, having stubs 44a and 44b at opposite ends thereof and being rotatable to three distinct positions on the lip 4 such that in each position the opening 18 is directly above one of the three wells 14. It is distinct in that the partition 12b is attached to the wall 2, rather than to the lid 16 as in FIGS. 7 and 8. The lip 4 has two sets of notches 41a and 41b distributed thereabout so that the aforementioned lid positions are achieved.

In another embodiment of this invention, shown in FIG. 10, comprising multiple wells 14 of various sizes, the depths of the wells 14 are the same, the wells 14 extending to the bottom of the wall 2 but their arcuate widths vary. The lid 16 is the same as in FIG. 9, the portal opening 18 being equal in arcuate width to that of the largest well 14a. The lid 16 is again rotatable to each of three positions corresponding to each of the three wells 14. The ends 42 of the stubs 44 fit in the notches 41 to secure the lid in one of the three aforementioned positions.

The largest well 14a with partitions 12a and 12b is similar to the well 14 in FIG. 2. However, wells 14b and 14c have partitions 47 and 48, respectively, with wings 50 and 52, respectively, laterally attached thereto externally of the wells 14b and 14c, respectively, and in the plane of the lip 4. The arcuate distance between outer edges 54 of the wings 50 is at least equal to the arcuate width of the largest well 14a, as is the arcuate distance between outer edges 56 of the wings 52.

Because the opening 18 is wider than wells 14b and 14c, when either of these wells is in use and the container is in the upside-down or tilted position of FIG. 5 granules would tend to flow along both sides of the well 14b or 14c and through that portion of the opening 18 extending laterally beyond the well 14b or 14c. By providing the wings 50 and 52, the opening 18 is prevented from communicating with the container except via the wells, therefore, the granules can emerge only through the wells 14. Wings 50 and 52 perform the same function in this embodiment as wing 13 does in the embodiment of FIG. 8.

The operation of the various embodiments of the invention shown in FIGS. 7, 9 and 10 is as follows: In each embodiment the lid 16 is rotated to the desired position which is determined by the desired amount of granules to be dispensed. Thereafter, the operation is the same as in the first embodiment discussed above.

The various embodiments of this invention may be manufactured preferably by injection molding of plastic material, although other conventional means would also be satisfactory if otherwise consistent with the teachings of the invention. The lid 16 and the wall-floor portion of the device could be molded separately and then assembled by seating the lid 16 on the lip. In the first embodiment of FIG. 1, the lid 16 could be secured to the lip 4 by glue or by heat-sealing, rendering it permanently seated. In the other three embodiments discussed, the lid 16 could be removably seated as shown or it could be made to snap on over the edge of the lip 4 in any suitable conventional manner so that it is rotatably seated on the lip 4. The lid 16 might, for example, have a skirt extending vertically down from its periphery. On the inner surface of this peripheral skirt could be a circumferential groove designed to accommodate the edge of the lip 4. As the lid 16 is seated, the lip 4 would snap into the groove and the lid 16 could be rotated.

There has thus been shown and described a granule dispensing regulator. Although specific embodiments of the invention have been described in detail, other variations of the embodiments shown may be made within the spirit, scope and contemplation of the invention.

Accordingly, it is intended that the foregoing disclosure and drawings shall be considered only as illustrations of the principles of this invention and are not to be construed in a limiting sense.

50 What is claimed is:

1. A granule dispensing regulator securably positionable in the neck of a container for regulating the dispensation of granules therefrom, comprising:

55 a peripheral wall with an outwardly extending peripheral lip at the top thereof;
an essentially cone-shaped floor peripherally connected to said wall, the apex of said floor being truncated by an aperture therein and extending towards the plane of said lip, said floor having two partitions extending vertically to the plane of said lip and inwardly from said wall along said floor, said partitions and said wall therebetween defining three sides of a well, said floor having a plurality of return openings near its periphery and externally of said well;
60 a lid seated on said lip and having an arcuate portal opening between its center and its periphery, said

portal opening being located above said well; and

a skirt extending downward from the edge of said portal opening nearest said center of said lid essentially to the plane of said aperture.

2. The granule dispensing regulator claimed in claim 1 wherein the smallest distance between the lowermost part of said skirt and said floor is larger than the largest linear dimension of said granules, and no larger than essentially twice said largest linear dimension.

3. A granule dispensing regulator, positionable in the neck of a container, for regulating the dispensation of granules therefrom, comprising:

a peripheral wall;

seating means associated with said wall for seating said wall in the neck of a container;

an essentially cone-shaped floor peripherally connected to said wall with its apex extending towards the plane of the top of said wall;

a plurality of pairs of spaced partitions extending inwardly from said wall and upwardly from said floor to said plane of the top of said wall, each of said pairs of partitions and said wall therebetween defining three sides of a well, said wells varying in depth and being equal in width;

a lid seated on top of said wall;

a portal opening in said lid between its center and its periphery, said portal opening being located above said well and being no wider than said well;

rotating means associated with said lid for rotating said portal opening to a position above each well as desired;

a skirt extending downward from the edge of said portal opening nearest said center of said lid toward said floor and between said partitions at an intermediary point of their inward extension, said lid, said skirt and the portions of said partitions extending beyond said intermediary point defining four sides of an interim region;

flow means associated with said floor for allowing granules to pour forth from said container into said interim region when said container is tipped upside down; and

return means associated with said floor for allowing granules to return to said container when said container is returned upright.

4. The granule dispensing regulator claimed in claim 3 wherein the smallest distance between the lowermost part of said skirt and said floor is larger than the largest linear dimension of said granules, and no larger than essentially twice said largest linear dimension.

5. The granule dispensing regulator claimed in claim 4 wherein said skirt extends to essentially the plane of said aperture.

6. A granule dispensing regulator, positionable in the neck of a container, for regulating the dispensation of granules therefrom, comprising:

a peripheral wall;

seating means associated with said wall for seating said wall in the neck of a container;

an essentially cone-shaped floor peripherally connected to said wall with its apex extending towards the plane of the top of said wall;

a plurality of pairs of spaced partitions extending inwardly from said wall and upwardly from said floor to said plane of the top of said wall, each of said pairs of partitions and said wall therebetween de-

fining three sides of a well, said wells varying in width and being equal in depth;

a lid seated on top of said wall;

a portal opening in said lid between its center and its periphery, said portal opening being located above said well and being no wider than the widest of said wells;

pairs of wings secured to the top of, and extending laterally from those pairs of spaced partitions defining all but the widest of said wells, the distance between the farthest edges of each pair of said wings being at least equal to the width of said portal opening;

rotating means associated with said lid for rotating said portal opening to a position above each well as desired;

a skirt extending downward from the edge of said portal opening nearest said center of said lid toward said floor and between said partitions at an intermediary point of their inward extension, said lid, said skirt and the portions of said partitions extending beyond said intermediary point defining four sides of an interim region;

flow means associated with said floor for allowing granules to pour forth from said container into said interim region when said container is tipped upside down; and

return means associated with said floor for allowing granules to return to said container when said container is returned upright.

7. The granule dispensing regulator claimed in claim 6 wherein the smallest distance between the lowermost part of said skirt and said floor is larger than the largest linear dimension of said granules, and no larger than essentially twice said largest linear dimension.

8. The granular dispensing regulator claimed in claim 7 wherein said skirt extends to essentially the plane of said aperture.

9. A granule dispensing regulator, positionable in the neck of a container, for regulating the dispensation of granules therefrom, comprising:

a peripheral wall;

seating means associated with said wall for seating said wall in the neck of a container;

an essentially cone-shaped floor peripherally connected to said wall with its apex extending towards the plane of the top of said wall;

a pair of spaced partitions extending inwardly from said wall and upwardly from said floor to said plane of the top of said wall, said partitions and said wall therebetween defining three sides of a well;

a lid seated on top of said wall with a portal opening therein between its center and its periphery, said portal opening being located above said well and being no wider than said well, the first of said partitions being connected to said wall, and the second of said partitions being connected at the top to said lid at one end of said portal opening, said lid being rotatable such that said second partition moves therewith toward said first partition rendering said well smaller thereby;

a wing connected to the top of, and extending laterally from said first partition in said plane of the top of said wall and external to said well, the width of said wing plus the width of said well when said well is at its smallest being at least equal to the width of said portal opening;

a skirt extending downward from the edge of said portal opening nearest said center of said lid toward said floor and between said partitions at an intermediary point of their inward extension, said lid, said skirt and the portions of said partitions extending beyond said intermediary point defining four sides of an interim region;
 flow means associated with said floor for allowing granules to pour forth from said container into said interim region when said container is tipped upside down; and
 return means associated with said floor for allowing

granules to return to said container when said container is returned upright.

10. The granule dispensing regulator claimed in claim 9 wherein the smallest distance between the lowermost part of said skirt and said floor is larger than the largest linear dimension of said granules, and no larger than essentially twice said largest linear dimension.

11. The granule dispensing regulator claimed in claim 10 wherein said skirt extends to essentially the plane of said aperture.
